(57) **CLAIM**

The ornamental design for a protection case for an electronic tracking device, as shown and described.

DESCRIPTION

FIG. 1 is a perspective view including the front, bottom, and side of a protection case for an electronic tracking device; FIG. 2 is a perspective view including the front, top, and side of the protection case for an electronic tracking device; FIG. 3 is a front elevation view of the protection case for an electronic tracking device; FIG. 4 is a rear elevation view of the protection case for an electronic tracking device; FIG. 5 is a side elevation view of the protection case for an electronic tracking device; FIG. 6 is an opposite side elevation view of the protection case for an electronic tracking device; FIG. 7 is a top plan view of the protection case for an electronic tracking device; and, FIG. 8 is a bottom plan view of the protection case for an electronic tracking device.

The protection case for an electronic tracking device is shown with a symbolic break in its length; the appearance of any portion of the article between the break lines forms no part of the claimed design.

The broken lines depict portions of the protection case for an electronic tracking device that form no part of the claimed design.
